DESIGN FOR A COMBINED STANDARD AND HOPPER FOR A FOOD SHREDDER

Joseph M. Majewski, Jr., Kansas City, Mo., assignor to Foster L. Talge doing business as Rival Manufacturing Company, Kansas City, Mo.

Application March 7, 1936, Serial No. 61,516

Term of patent 7 years

To all whom it may concern:

Be it known that I, Joseph M. Majewski, Jr., a citizen of the United States, residing at Kansas City, in the county of Jackson and State of Missouri, have invented a new, original, and ornamental Design for a Combined Standard and Hopper for a Food Shredder, of which the following is a specification, reference being had to the accompanying drawing, forming part thereof, in which,

Figure 1 is a front perspective view of a combined standard and hopper for a food shredder showing my new design.

Figure 2 is a rear perspective view thereof.

I claim:

The ornamental design for a combined standard and hopper for a food shredder, substantially as shown.
